US00D725605S

(12) **United States Design Patent**
Hashimoto et al.

(10) **Patent No.:** US D725,605 S
(45) **Date of Patent:** ** Mar. 31, 2015

(54) **RELAY**

(71) Applicant: **Omron Corporation**, Shimogyo-ku, Kyoto (JP)

(72) Inventors: **Ryuichi Hashimoto**, Kyoto (JP); **Keisuke Yano**, Kyoto (JP)

(73) Assignee: **Omron Corporation**, Kyoto (JP)

(**) Term: **14 Years**

(21) Appl. No.: **29/475,409**

(22) Filed: **Dec. 3, 2013**

Related U.S. Application Data

(62) Division of application No. 29/433,370, filed on Sep. 28, 2012, now Pat. No. Des. 697,033.

(57) **CLAIM**

The ornamental design for a relay, as shown and described.

DESCRIPTION

FIG. 1 is a top, front and left side perspective view of a relay showing an embodiment of our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict environmental subject matter only and form no part of the claimed design.

1 Claim, 4 Drawing Sheets
